BUCKLE

Albert Meehan, Baltimore, Md.

Application September 7, 1935, Serial No. 39,508

4 Claims. (Cl. 24—180)

The present invention relates to buckles and has for its object an improvement in the structure whereby, in conjunction with the strap or belt portion thereof, the buckle may be easily attached or detached. The present buckle may be used on belts for personal wear, shoe straps, wrist-watch straps and for such other purposes as a buckle of this type would be useful.

The present buckle, in some respects is a modification over my U. S. Patent #1,856,775, issued May 3rd, 1932, and U. S. Patent #1,856,776, issued May 3rd, 1932 to Thomas A. McDermott and myself.

One of the features of advantage resides in the mode of operative attachment of the buckle to the coacting strap or belt end, for removal or replacement.

Another feature of advantage is in the structure of the buckle the same being made in preferably three main parts, two of said parts forming the buckle-belt interlocking and attaching means, the third part being a front gripper plate attached to one of the buckle faces by suitable means and which front plate forms a means to open the buckle from the strap or belt, and which also may be of ornamental nature, and in some instances be made of a precious metal while the buckle itself may be made of a baser metal.

The foregoing, and other features of advantage will appear, as the herein description appears and it is obvious that modifications may be made in the structure herein without departing from the spirit hereof or the scope of the appended claims.

35 In the drawing,

Fig. 1 is a sectional view taken on the line 1—1, Fig. 3, looking in the direction of the arrows, but including the strap or belt, also in section;

Fig. 2 is a plan view of the buckle with the front portion opened;

Fig. 3 is a side view of the buckle;

Fig. 4 is an opposite side view of the buckle as shown open, in Fig. 2;

Fig. 5 is a sectional view of a slightly modified form of buckle, similar to the sectional view of Fig. 1; and

Fig. 6 is a front elevation of the gripper plate of Fig. 5.

50 As shown in Figs. 2 and 3, the buckle comprises a back plate 3, having a right angled floor portion 12, said latter portion at its outer extended edge having a slot S therein, and into which is connected a curled, cylindrical and narrow extension 10, which is integral with the front

buckle plate 2, thereby to form a hinge between the front and back buckle plates.

The buckle plates are each provided with angled, coacting snap locks 7 and 8, snap lock 7, on back plate 3, being integral with said plate and of curved contour and having a thinned frontal edge 7'.

Front plate 2 also has a curved, integral snap lock 8, Fig. 3, and the frontal edge 8' thereof is also thinned. Snap lock 8, when the buckle 10 is closed, as in Fig. 3, overlaps snap lock 7, with a locking grip and as both of these lock members are resilient they by-pass, one over the other when the buckle members are separated, or closed, with a snap action.

15 The complete buckle structure, as above described is relatively small, and as the snap lock 7—8 is smooth when closed it is difficult to open.

To overcome this feature, a gripper plate 1 of, generally, larger dimension than the front buckle plate 2 is suitably affixed to the outer, exposed face of buckle plate 2, so that the peripheral edge thereof is extended beyond the dimensions and contour of the buckle plate 2, thereby to enable the fingers of the user to grip said gripper plate 1 to open or close the buckle plate 2. This gripper plate has a second function, and that is to form an ornamental front for the buckle, where it is used on belts for personal wear to receive monograms and the like, thereon, or any other form of embellishment, as desired. The front plate may be in other contours than shown, as a concession to such embellishment, but it still will perform the useful purpose of a manually manipulable grip.

30 The belt portion shown fragmentarily and in part section in Fig. 1, is provided at one end with a looped portion, generally denoted by 5, the loop being formed by folding the end of belt portion B' upon itself and then stitching the end to the belt as by stitches 6, or the loops may be formed by other means.

35 The inside face 5' of the belt loop, as in Fig. 1, is provided with two spaced apertures, which register with and permit the passing therethrough of two belt latch pins 4—4 which are firmly riveted to the back buckle plate 3, as at 11, Fig. 3. As thus described, the complete buckle assembly, as shown in Fig. 3, may be removed from the loop 5, by opening the buckle, as in Figs. 2 and 3, and then by tipping the back buckle plate 3 upwardly from its hinge end, as viewed in Fig. 1, and in the direction shown by the arrow in Fig. 2, the loop 5 is pried open and the latch pins 4—4 are withdrawn from the holes.

A reverse action replaces the back buckle to position as shown in Fig. 1.

The opposite end B of the belt, Fig. 1, is provided with a series of perforations p, which are aligned with one another in spaced relation, the spacing of which registers with the spacing of the pins 4-4, so that the end B may be adjusted on the pins 4, to conform to a proper belt adjustment.

10 The ends of the pins 4-4, extend beyond the outer face of the belt end B, and the extensions of said pins fit into apertures 9-9 Fig. 2, in the front buckle plate 2, when the buckle is closed and thus the riveted and extended ends are simultaneously supported against the opposing strains of the belt ends B and B'. These strains flatten loop 5 and cause it to hug the back buckle plate 3. The portion of the loop 5 at the rear of the back plate acts as a cushion between the person of the wearer and the back plate.

In Figs. 5 and 6 the front gripper plate 1 as well as the front 2 may have the perforations 9 extended therethrough as at 9'-9', Figs. 5 and 6, with the pins 4-4 extended further so as to enter said holes 9'-9' in the front gripper plate 1, and such extensions 4'-4' may form the central motif of a design such as shown at c Fig. 6.

What I claim is:

1. A buckle of the class described, comprising a back plate and a front plate, an offset hinge connecting the two, a snap lock carried by each plate cooperating to mutually disengage and engage to open and close said plates about said hinge, said locks being located oppositely of said hinge, latch pins carried by one of their ends by one of said plates, the other plate being provided with spaced apertures to form end engaging seats for the opposite ends of said pins, and a gripper plate carried by said other plate, said gripper plate being provided with spaced apertures in registry with the apertures of said other plate.

2. A buckle for a belt comprising a back plate having rising from its opposite sides a snap member and a rigid member, means rigid with said plate for holding the inner end of a belt, said members having their front ends disposed forwardly of said inner end whereby to form side

guides for the outer end of the belt, a swingable front plate hingedly mounted on the forward end of said rigid member, and a snap member extending from the other side of said front plate, said second snap member being adapted to cooperate in releasable locking engagement with the first snap member, said means and said front plate adapted also to hold said outer end of the belt.

3. A buckle for a belt having a perforated inner end and a perforated outer or front end, said buckle including a back plate having side members extending substantially as far forwardly as the front of said front end, at least one latch pin carried by said plate and adapted to pass through a perforation of each end of the belt, one of said members having at the top thereof an integral hinge portion, the other member being plain and forming a snap element, a swingable front plate having at one of its sides an integral hinge portion which cooperates with the first portion, said latter plate having therein at least one aperture wherein the front end of the pin finds a seat in the closed position of said front plate, the other side of said front plate having thereon a plain member forming a snap element for lockingly cooperating with the first element, and a manipulating plate rigid with said front plate whereby to unlock the snap elements.

4. In a belt buckle, a swingable front plate, a back plate including means for permanently holding the inner end of a belt, said means including latch pins which are rigid with the plate, said end being perforated, there also being perforations in the front end of the belt, the pins being adapted to releasably engage in the front perforations; side members rising from said back plate and having rear to front dimensions equal to the combined rear to front dimensions of said ends, hinge means connecting one side of said front plate and the front part of one of said members, the other member being a plain snap lock element, and a plain snap lock element extending from the other side of said front plate for cooperating with the first mentioned element.

ALBERT MEEHAN.
